FOREIGN PATENT DOCUMENTS

WO WO 2017/006404 A1 1/2017

Primary Examiner — Rosemary K Tarcza*Assistant Examiner* — Nathaniel D. Buckner(74) *Attorney, Agent, or Firm* — Bergman & Song LLP; Michael Bergman(57) **CLAIM**

The ornamental design for a charging station, as shown and described.

DESCRIPTION

FIG. 1 is a front perspective view of a charging station, of our new design;

FIG. 2 is a rear perspective thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures depict portions of the article which form no part of the claimed design.

1 Claim, 8 Drawing Sheets(56)
